(57) **CLAIM**

The ornamental design of a multi-outlet spray nozzle as shown and described.

DESCRIPTION

FIG. 1 is a downward isometric view of one embodiment of a multi-outlet spray nozzle in accordance with the disclosed principles;

FIG. 2 is a front elevation view of the multi-outlet spray nozzle illustrated in FIG. 1;

FIG. 3 is a rear elevation view of the multi-outlet spray nozzle illustrated in FIG. 1;

FIG. 4 is a left-side elevation view of the multi-outlet spray nozzle illustrated in FIG. 1;

FIG. 5 is a right-side elevation view of the multi-outlet spray nozzle illustrated in FIG. 1;

FIG. 6 is a top view of the multi-outlet spray nozzle illustrated in FIG. 1;

FIG. 7 is a bottom view of the multi-outlet spray nozzle illustrated in FIG. 1; and,

FIG. 8 is an upward isometric view of another embodiment of a multi-outlet spray nozzle in accordance with the disclosed principles.

The portions of the Figures shown in broken lines in the view are for illustrative purposes only and form no part of the claimed design. Any broken away symbols in the Figures indicate the appearance of any portion of the article between the break lines form no part of the claimed design.

1 Claim, 7 Drawing Sheets
